COOLING SYSTEM ANALYZER

Robert B. Edelmann, Chicago, Ill., assignor to E. Edelmann & Co., Chicago, Ill., a corporation of Illinois

Application December 5, 1955, Serial No. 39,145

Term of patent 3½ years

(Cl. D52—1)

Figure 1 is a perspective view of a cooling system analyzer, showing my new design.

Figures 2, 3, 4 and 5 are, respectively, top plan, front elevation, side elevation, and bottom plan views of the same.

I claim:

The ornamental design for a cooling system analyzer, substantially as shown.
